US00D733319S

(12) **United States Design Patent**
Somers et al.

(10) **Patent No.:** **US D733,319 S**
(45) **Date of Patent:** **** Jun. 30, 2015**

(54) **ULTRASONIC TREATMENT WAND**

(71) Applicant: **Celleration, Inc.**, Eden Prairie, MN (US)

(72) Inventors: **Micah Tobias Somers**, Minneapolis, MN (US); **Brett Ryan Johnson**, Roseville, MN (US); **Kyle Adam Gudmunson**, Minneapolis, MN (US); **Ryan Glen Tetzloff**, Minnetonka, MN (US); **Doug Duchon**, Chanhassen, MN (US)

(73) Assignee: **Celleration, Inc.**, Eden Prairie, MN (US)

(**) Term: **14 Years**

(21) Appl. No.: **29/479,047**

(22) Filed: **Jan. 10, 2014**

(51) **LOC (10) Cl.** **24-00**

(52) **U.S. Cl.**

USPC **D24/231**

(58) **Field of Classification Search**

(57) **CLAIM**

We claim the ornamental design for an ultrasonic treatment wand, as shown and described.

DESCRIPTION

FIG. 1 is a front corner perspective view of an ultrasonic treatment wand according to an embodiment of the invention. FIG. 2 is a left side elevational view of the ultrasonic treatment wand according to an embodiment of the invention. FIG. 3 is a right side elevational view of the ultrasonic treatment wand according to an embodiment of the invention. FIG. 4 is a front elevational view of the ultrasonic treatment wand according to an embodiment of the invention. FIG. 5 is a rear elevational view of the ultrasonic treatment wand according to an embodiment of the invention. FIG. 6 is a bottom view of the ultrasonic treatment wand according to an embodiment of the invention; and, FIG. 7 is a top plan view of the ultrasonic treatment wand according to an embodiment of the invention. In the drawings, the broken lines depict unclaimed subject matter only and form no part of the claimed design.
